UNITED STATES PATENT OFFICE.

HARLEY E. HUTCHISON, OF HOTCHKISS, COLORADO.

CONTAINER.

Application filed October 30, 1922. Serial No. 597,894.

To all whom it may concern:

Be it known that I, HARLEY E. HUTCHISON, a citizen of the United States, residing at Hotchkiss, in the county of Delta and 5 State of Colorado, have invented certain new and useful Improvements in Containers, of which the following is a specification, reference being had to the accompanying drawings.

10 This invention relates to improvements in containers and more particularly to improvements in a container adapted for use upon the counters of grocery stores and the like for dispensing honey, sirups and the 15 like.

An important object of the invention is to provide a device of this character which is extremely simple in its construction, which may be very readily cleansed and is therefore sanitary, and by means of which sirups 20 of the character described may be readily dispensed.

These and other objects I attain by the construction and arrangement shown in the 25 accompanying drawings wherein for the purpose of illustration is shown a preferred embodiment of my invention and wherein like reference characters designate like parts throughout.

30 In the drawings:—

Figure 1 is a sectional view taken through a container constructed in accordance with my invention; and

35 Figure 2 is a detail view showing the manner of mounting the outlet in the container.

Referring now more particularly to the drawings, the numeral 10 indicates a container formed of glass and of the desired 40 size and having a large top or filling opening 11 provided with a suitable closure 12 preferably formed of the same material. The opening 11 should be of sufficient size to permit ready access to the jar for the 45 purpose of cleansing the same. Adjacent its lower end slightly spaced thereabove, an opening 13 is formed in the container within which is arranged a gasket 14.

The numeral 15 designates a metallic pipe 50 formed upon its inner end with a shoulder 16 which is extended through the gasket 14 and which has interposed between its shoulder 16 and the wall of the container a gasket 17. The outer end of the pipe 15 projects beyond the outer face of the container wall and is internally and externally 55

screw-threaded, as indicated at 18 and 19 respectively. The external screw-threads 19 are adapted for coaction with a knurled clamping nut 20 between which and the 60 outer wall of the container is arranged a gasket 21.

It will be noted that the opening in the wall of the container is of greater size than the pipe 15 which is directed therethrough 65 and that the gaskets 16 and 21 are in the form of washers having an internal opening of the same size as the diameter of the pipe 15 and an external diameter greater than the diameter of the opening 13. Accordingly, when the operating or clamping nut 20 is turned, the gaskets 16 and 21 as they are compressed will be forced into the opening between the pipe 15 and the edge of the opening 13 thereby compressing the 70 gasket 14 disposed within this opening in addition to compressing the gaskets 16 and 21 and assuring a tight fit of the pipe 15 within the opening 13 without the necessity of applying sufficient pressure thereto to 75 break the walls of the container. The internal screw-threads of the pipe 15 are adapted for the reception of the threaded shank of an outlet cock 22 of any suitable 80 description.

The numeral 23 designates the base of the container which is preferably formed of wood and is provided in its upper end with a socket 24 closely fitting the base of the container so as to prevent movement thereof. The base or support 23 is preferably provided with a central opening 25 so that a pan or the like, as indicated at 26, containing hot water may be placed within the base to heat the contents of the container 90 10 in event of the same becoming candied. Since the clamping element or washer 20 by means of which the spigot outlet is placed in position within the container wall is readily operable by means of the hand and 95 since the customers of a store are often inclined to handle such objects, I make the socket 24 in which the bottom of the container is seated, of sufficient depth that the base projects upwardly to receive this operating nut and form in the side wall of the socket 24 a recess 26 receiving the lower portion of this washer and preventing engagement of the fingers thereto. This recess is of just sufficient depth to permit insertion of the container when the washer 100 110 115 120 125 130 135 140 145 150 155 160 165 170 175 180 185 190 195 200 205 210 215 220 225 230 235 and accordingly rotation of the washer without first elevating the container will be impossible.

From the foregoing it is believed to be obvious that a container constructed in accordance with my invention provides a device which may be readily cleansed and from which the parts may be readily removed for cleansing and which at the same time is safe-guarded against the meddling of customers who are curious. It will furthermore be obvious that the structure hereinbefore set forth is capable of some change and modification without materially departing from the spirit of my invention and I accordingly do not limit myself to such specific structure except as hereinafter claimed.

I claim:

1. The combination with a container of the type described having formed through the wall thereof an opening adapted for the reception of an outlet fitting, and means including a hand operated clamping element for securing the outlet fitting in position, of a base for said receptacle coacting with the clamping element to prevent rotation thereof when the container is in position upon the base.

2. The combination with a container of the type described having formed through the wall thereof an opening adapted for the reception of an outlet fitting, and means including a hand operated clamping element

for securing the outlet fitting in position, the clamping element being disposed exteriorly of the container and releasing the outlet fitting upon movement thereof in a direction away from the container, of a base for said receptacle supporting the receptacle and having portions engaging the clamping element preventing movement thereof in a direction away from the container when the container is in position upon the base.

3. The combination with a container of the type described having formed through the wall thereof an opening adapted for the reception of an outlet fitting, and means including a hand operated clamping element for securing the outlet fitting in position, the clamping element being disposed exteriorly of the container and releasing the outlet fitting upon movement thereof in a direction away from the container, of a base for said receptacle having a socket receiving the receptacle and maintaining the same against transverse shifting with relation to the base, one wall of said socket being provided with a recess receiving the lower portion of said clamping element, the outer wall of said recess engaging the outer face of the clamping element to prevent movement thereof in a direction away from said container.

In testimony whereof I hereunto affix my signature.

HARLEY E. HUTCHISON.
